(57) **CLAIM**

We claim the ornamental design for a cooking pot lid handle, as shown and described.

DESCRIPTION

FIG. 1 is a top plan view of a cooking pot lid handle of the claimed design;

FIG. 2 is a front elevational view of the cooking pot lid handle shown in FIG. 1;

FIG. 3 is a perspective view of the cooking pot lid handle shown in FIG. 1;

FIG. 4 is a rear elevational view of the cooking pot lid handle shown in FIG. 1;

FIG. 5 is a bottom plan view of the cooking pot lid handle shown in FIG. 1;

FIG. 6 is a top plan view of the cooking pot lid handle shown in FIG. 1 attached to a lid;

FIG. 7 is a front elevational view of the cooking pot lid handle shown in FIG. 6;

FIG. 8 is a rear elevational view of the cooking pot lid handle shown in FIG. 6;

FIG. 9 is a perspective view of the cooking pot lid handle shown in FIG. 6;

FIG. 10 is a left side elevational view of the cooking pot lid handle shown in FIG. 6; and,

FIG. 11 is a right side elevational view of the cooking pot lid handle shown in FIG. 6.

The ornamental design which is claimed is shown in solid lines in the drawings. The broken lines in the drawings are for illustrative purposes only and form no part of the claimed design.
